PREFABRICATED BUILDING UNIT FOR A KITCHEN

Tadashi Hanaoka, Kawasaki, Isao Kaneko, Tokyo, and
Iwao Shiina, Yamato, Japan, assignors to Misawa
Homes Co., Ltd., Tokyo, Japan

Filed Nov. 6, 1972, Ser. No. 303,809

Claims priority, application Japan Sept. 19, 1972

Term of patent 14 years

Int. Cl. D25—02

U.S. Cl. D13—1 R

FIG. 1

FIG. 3

FIG. 2

FIG. 4

FIG. 7

FIG. 6

FIG. 5

FIG. 8

FIG. 1 is a top plan view of a prefabricated building unit for a kitchen showing our new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a cross sectional view on line VI—VI of FIG. 2, also showing the wall to which the unit is mounted in dashed lines;

FIG. 7 is a cross sectional view on line VII—VII of FIG. 2; and

FIG. 8 is a perspective view thereof; without the kitchen equipment installed therein.

The elements shown in dashed lines in the Figures are for illustrative purposes.

We claim:

The ornamental design for a prefabricated building unit for a kitchen, as shown and described.
